APPARATUS FOR CLEANING METAL

John A. Falor, Detroit, Mich., assignor to Kolene Corporation, Detroit, Mich.

Application March 19, 1956, Serial No. 572,449

2 Claims. (Cl. 210—55)

This invention relates to an apparatus for cleaning metals, and more particularly, to an apparatus for removing sludge from a molten salt bath metal cleaning device.

During the past few years, the metal manufacturing industries have begun to use molten salt baths for the purposes of cleaning rust, scale, and other surface impurities of a similar nature from metallic parts during the manufacturing and fabricating operations. The general processes and salt compositions utilized are found in various prior art patents, such as, for example, Patent No. 2,458,661 of January 11, 1949, and No. 2,468,006 of April 19, 1949.

In the use of molten salt baths cleaning apparatuses, during the cleaning operation wherein the metallic parts are dipped into the molten salt baths, the various impurities removed from the metal form a sludge within the dipping tank. One of the problems in utilizing this molten salt bath process is that of removing the sludge, while at the same time avoiding the necessity of cooling down the salt bath or of interrupting the operation of the bath for any period of time.

Thus, this invention relates to a sludge removing apparatus which has for its object the expeditious removal of sludge in a molten salt bath tank, and at the same time, provides for a quick removal of the sludge without shutting down the bath or cooling the salt, and without losing the heat contained in the molten salt.

A further object of this invention is to provide tray devices formed within a chamber through which the molten salt from the molten salt bath is passed. The chamber is substantially quiescent so that the sludge floating and contained within the salt bath settles into these various trays. The trays may then be individually removed for the purposes of cleaning out the sludge deposited therein.

Still a further object of this invention is to provide removable sludge catching trays wherein one tray is removed for cleaning, and wherein this tray is initially positioned to catch the most amount of deposited sludge, and wherein once this particular tray is removed, the remaining trays are moved into position to successively be placed in the position of catching the most amount of sludge.

Still a further object of this invention is to provide a series of trays movable in a line so that one tray may be removed after it becomes filled with sludge, and the remaining trays may be advanced one position; and wherein a clean tray may be substituted at the end of the line of trays, all of this being accomplished without having to shut down the molten salt bath operation, and without losing any large amount of heat.

Yet an additional object of this invention is to provide a means for removing a sludge catching tray, which means consists of a combined cover and rail support means wherein the tray is removed by one simple and quick operation to thereby avoid any large amount of heat loss from the molten salt bath tank.

These and other objects of my invention will become

2

apparent upon reading the following description, of which the attached drawings form a part.

Referring to the drawings in which:

Fig. 1 is a top view of a salt bath pot formed in accordance with this invention and shown with the cover removed.

Fig. 2 is a cross-sectional view taken on line 2—2 of Fig. 1, and illustrates the pot with the cover in position.

Fig. 3 is a view taken on line 3—3 of Fig. 1.

Fig. 4 illustrates the combined cover and support rail means and the removable tray, suspended therefrom.

In the operation of a molten salt bath tank, it is necessary to heat the molten salt and to retain it in its heated condition to provide an area which is free to receive metal parts to be cleaned, and at the same time provide a means for removing sludge, which is deposited from the metal. To accomplish these functions, the device which forms an embodiment of this invention, and which is illustrated schematically in Fig. 1, is shown as comprising a pot generally designated as 10 which is divided into three sections. These sections are the work zone 11, the heating chamber 12, and the sludge removal chamber 13.

As seen in Fig. 1, the pot is a generally elongated, rectangular shaped tank. The heating chamber 12 is formed alongside the pot and includes heating coils 16 whose function is to heat the molten salt and maintain the salt at some predetermined temperature. These coils may be operated by gas or electricity or any other suitable heating manner. The construction of these coils forms no part of this invention, and therefore, they are only illustrated and described broadly.

Also within this heating chamber are positioned a number of agitators 17 which are schematically shown in Fig. 1. These agitators may consist of propellers on the ends of driven shafts, and may be driven by any suitable motor means. The function of these agitators will be described later.

The heating chamber opens into the work zone 11 of the pot by means of openings 19 formed in the wall which separates the chamber from the work zone.

At one end of the pot a duct 21 is provided and opens into the heating chamber through an orifice 22, and opens into the sludge chamber 12 through a second orifice 23 formed at the opposite end of the duct (see Fig. 2).

The sludge chamber is provided with an opening 24 at the end opposite to which it is connected to the duct 21. Thus, it can be seen that, in operation, salt is circulated from the work zone through the openings 19 into the heating chamber 12 where the salt is maintained at temperature by the heating coil 16. The agitators 17 with their propeller blades 18 agitate the salt to evenly heat the material, and at the same time to direct the salt which is heated through the orifice 22, through the duct 21, then through the orifice 23, and into the sludge chamber 13.

The molten salt passing through the sludge chamber exits through the opening 24 back into the work zone. All during this time, the level of the salt bath is maintained as roughly designated at 25.

The sludge chamber is a relatively quiescent area through which the salt passes at a relatively slow rate so that sludge tends to settle out to the floor of this chamber.

In order to catch this sludge, a plurality of trays 30 are provided. As can be seen in Fig. 1, the trays are aligned in an end to end relationship with each other, and are located at the bottom of the sludge chamber 13.

These trays are supported within the sludge chamber by means of rails 31 at the top of the chamber and operating wheels 33 on the rails, which wheels are formed in pairs connected by cross-bars 32.

The trays themselves are suspended by means of rods 34 from the cross bars 32. Therefore, the trays may be

rolled along the rails and moved for purposes to be later described.

The sludge chamber is provided with covers which are generally designated as 35, which covers are provided with removable end sections 36 and 37. The cover section 36 is positioned above the tray which is located at the entrance point or the duct connection point of the sludge chamber. This cover is formed integral with, or mechanically connected to, the rail section of this area, and this rail section 38 is formed separately from the remaining rail portion.

The heating chamber is provided with a cover, as is the work zone chamber, and openings may be provided to accommodate the agitators 17 and to permit the dipping of work pieces into the work zone. The function of all these covers is to prevent heat from escaping from the pot and to thereby reduce the expense of heating the salt, and to keep the salt in its molten condition.

In operation, salt may be added in its non-molten state to the heating chamber as required to maintain the level of the chamber, and in addition, salt enters into this chamber from the work zone through the openings 19 as previously described. The salt, which is then agitated for even heating and is directed through the duct 21, passes over the first tray 30 near the duct, and at this point deposits a great deal of the sludge contained therein. The salt continues through the chamber and deposits more and more sludge in each of the trays, but in lesser amounts as the trays are further spaced from the entry point.

When the first tray 30 has become sufficiently loaded with sludge, the cover 36 is lifted upward by means of a crane or the like to thereby remove the attached rail 38 and the trays supported by this rail. The tray is then slid off the rail for cleaning. Once the tray is removed from the rail the cover is again replaced, and this replacement takes place very quickly so that a minimum amount of heat is lost and a minimum amount of time is lost with the cover out of position.

Thereafter the end cover 37 is lifted, the remaining trays 30 are advanced one position so that the second tray now becomes the first tray, and a clean tray is inserted in the last position.

In order to hold the trays in tight alignment with each other, and to facilitate moving from one position to the next in advancing them, links 40 join the rollers and the cross bars of each tray. These links may be in any form, such as a heavy piece of metal hooked to each cross bar, or any other sort of mechanical linkage. It is only important that whatever linkage is selected functions to keep the trays together and to join the trays so that in moving them along, one tray may be moved, and all the others will follow in the same motion. At the same time, the link must be disengageable when the tray is lifted upwardly.

As can be seen, the trays are successively advanced and, as they get into the end position, they become full of sludge and are removed, and are thereby replaced with a clean tray at the opposite end. This system results in expeditious removal of the trays, and does not require the shutting down of the salt bath, and results in a saving of heat because of the speed at which the trays may be removed and replaced.

The clean tray that is inserted into the sludge chamber may be the same one that was originally removed, and which is quickly cleaned, or in the alternative, may be an extra tray. Thereby, the device may be operated with

an extra tray which is always kept clean and always ready to be inserted into the end position when the sludge loaded tray is removed.

The configuration of the support rails and the means for connecting the trays to the support rails may be varied within the mechanical limitations required to support the weight of the tray. It is only important that the trays be movable and may be advanced one by one from one end of the feeding chamber to the opposite end, and then be removed when the tray is full of sludge.

This invention may be further developed within the scope of the following attached claims. Accordingly, it is desired that the foregoing description be read as being merely illustrative of an operative embodiment of this device, and not in a strictly limiting sense.

Having fully described at least one operative embodiment of this invention, the following is now claimed:

1. An apparatus for cleaning metals by a molten salt bath comprising an elongated pot having a work zone 20 wherein metals to be cleaned are dipped; a sludge chamber formed along one side and communicating into the pot and means to cause molten salt in the pot to pass through the length of the chamber for removal of sludge; a row of sludge trays positioned within the chamber in end to end alignment and suspended from a rail secured at the top and extending the length of the chamber, said trays being movable along the length of the rail; a cover covering the top of the chamber and having a removable section at each end of the chamber, the tray at one end 25 of the chamber being removable for cleaning and being insertable, after cleaning, into the opposite end by advancing the remaining trays in the chamber to fill the space left by the removed tray, the rail section upon which the removable tray is suspended being formed as a separate section from the remainder of the rail and the cover section being connected to this rail section, whereby removal of the cover section removes the rail section and its suspended removable tray.
2. An apparatus for cleaning metals by a molten salt bath comprising a pot having a work zone wherein metals to be cleaned are dipped and an elongated sludge chamber closed at its top by a cover, means for passing the molten salt into one end of the chamber and out the other 40 whereby sludge settles out of the salt and drops to the bottom of the chamber, a plurality of sludge trays positioned at the bottom of the chamber in end to end alignment with one another to catch the settled sludge, a rail at the top of the chamber and extending the length of the chamber, means for movably suspending each tray from the rail and for movement along the length of the rail, said cover having removable sections at each end of the chamber, the tray at the salt entrance end of the chamber being removable for cleaning, and the remaining trays being movable along the rail to fill the space of the removed tray, whereby a clean tray may be inserted into the chamber at the opposite, salt exit, end, the rail section from which the removable tray is suspended being formed separate from the remaining part of the rail and being connected to the removable cover section, so that removal 45 of the cover simultaneously removes the removable tray.
